UNITED STATES PATENT OFFICE.

ANTHONY F. BARRO, OF NEW YORK, N. Y., ASSIGNOR OF ONE-HALF TO ALPHONSE A. DIBBLEE, OF NEW YORK, N. Y.

RAZOR-BLADE HOLDER.

1,306,516.

Specification of Letters Patent. Patented June 10, 1919.

Application filed November 1, 1917. Serial No. 199,753.

To all whom it may concern:

Be it known that I, ANTHONY F. BARRO, a citizen of the United States, and a resident of New York, county and State of New York, have invented a certain new and useful Improvement in Razor-Blade Holders, of which the following is a full, clear, and exact specification.

This invention relates more particularly to a class of devices adapted to be used in conjunction with safety razor blades.

My invention has for its object primarily to provide a device, or holder designed to be employed to enable the blades of safety razors to be readily sharpened when dulled by use, and which is of a form whereby blades of various types may be removably applied thereto for being sharpened, thus meeting the requirement for a device of this class adapted to be used in conjunction with safety razors of different forms. The invention consists essentially of a body member with a flat surface having extension members protruding upwardly therefrom for removably receiving a safety razor blade. To the body member may be pivoted one or a number of retaining elements each adapted to be swung upon the blade to coact with the extension members for clamping the blade on the body member, and integral with each retaining element is a clip adapted to be guided into detachable engagement with the body member for releasably locking the body member and the retaining element together.

A further object of the invention is to provide a razor blade holder of a simple, efficient and durable construction which is susceptible of being made in desired shapes and sizes.

With these and other objects in view, the invention will be hereinafter more fully described with reference to the accompanying drawing forming a part of this specification in which similar characters of reference indicate corresponding parts in all the views, and will then be pointed out in the claim at the end of the description.

In the drawing, Figure 1 is a fragmentary

view showing a top plan of one form of 50 razor blade holder embodying my invention.

Fig. 2 is a fragmentary view showing also a top plan of the holder with one of its retaining elements in a position for holding a safety razor blade.

Fig. 3 is a fragmentary view showing a side elevation of the device.

Fig. 4 is a fragmentary view showing an elevation of the opposite side of the device.

Fig. 5 is a plan of one form of safety 60 razor blade adapted to be used with the holder.

Fig. 6 shows a plan and an edge view of another form of safety razor blade, and

Fig. 7 is a plan of still another form of 65 safety razor blade.

The device has a body or surface member 10 which is preferably in the form of a flat bar of metal, and on one end of the bar is a handle 11 which may be of any desired 70 shape and size to permit the holder to be conveniently manipulated for sharpening a razor blade. The central part of the side edges of the bar is enlarged, at 12, to provide a bearing surface, and part of the bar 75 adjacent to the handle may be reduced in width to form on the contiguous edges of the bar two shoulders 13 and 14 extending in opposite lateral directions. A portion of the free end of the bar, or body member 80 10 may be cut-out to form at the corner of the bar opposite to the shoulder 14 another shoulder 15, and on the edge of the bar opposite to this third shoulder is a laterally protruding elongated lug, as 16, having a 85 number of upwardly projecting spaced extension members or knobs 17. The extension members 17 are so arranged that the well-known forms of safety razor blades, illustrated at 18 and 19 Figs. 5 and 7, may 90 be removably positioned thereon by the extension members being disposed through the openings 20 and 21 of the blades, and these extension members are of lengths approximately similar to the thicknesses of the 95 blades. In Fig. 6 is shown still another well-known form of safety razor blade, as 22, having a bead 23 on one of its edges,

- and this blade is also adapted to be placed on the extension members for being sharpened, as will be hereinafter more particularly explained.
- 5 On the bar, or body member 10 may be one or a number of retaining elements, as 24 and 25, which coöperate with the extension members 17 for removably holding the razor blades on the bar. The retaining 10 element 24 is preferably formed of a strip 26 of flat metal having one of its ends pivoted, at 27, to the bearing surface 12 of the bar so as to be swung back and forth in close proximity to the bar from the shoulder 13 to the shoulder 15 of the bar. This strip is of a length so that when the retaining element 24 is swung upon the bar toward the handle 11 its second end will protrude slightly beyond the shoulder 13 15 and when the retaining element is swung upon the bar toward its free end the second end of the element will protrude slightly beyond the shoulder 14. Projecting laterally from one of the edges of the strip 26 20 are two lugs or fingers 28 and 29 for being guided toward the extension members 17 when this retaining element is swung on the bar upon the shoulder 15, and these fingers are spaced apart at a greater distance than 25 the extreme lengths of the openings of the razor blades. On the free end of the strip 30 is a clip 30 serving to releasably lock the strip 26 to the bar 10, and this clip is preferably formed by bending the free end of 35 the strip 26 in the fashion of a hook to allow the hook to be removably disposed over the shoulders 13 and 15 of the bar.
- To sharpen forms of either of the razor blades 18 or 19, the blade is arranged on the 40 lug 16 of the bar 10 so that the extension members 17 will be inserted through the opening or openings of the blade. The retaining element 24 is then swung from its position in engagement with the shoulder 45 13 of the bar 10 to the position indicated, at 31, Fig. 1. The strip 26 of the retaining element together with the fingers 28 and 29 will thereby be disposed upon the razor blade, and the clip or hook 30 will engage 50 the shoulder 15 of the bar so that the blade will be releasably clamped in the holder which in turn may be sharpened in the usual manner of honing razors.
- The retaining element 25 is also preferably 55 formed of a strip 32 of flat metal having one of its ends rotatably held to the pivot 27 on top of the retaining element 24 so as to be swung crosswise over the bar toward and from the shoulder 14 as well as toward 60 and from the shoulder 15 of the bar. This strip corresponds in length to the strip 26 of the retaining element 24 so that when moved on the bar toward the handle 11 its free end will protrude somewhat beyond the 65 shoulder 14 and when the strip is swung to-
- ward the free end of the bar its second end will extend somewhat beyond the shoulder 15. Projecting from the central part of the edge of the strip 32 is an elongated flange 33 which is disposed toward the bar 10, and 70 this flange is of a width approximately similar to the thickness of the strip 26 of the retaining element 24 so as to contact with the bar 10 when guided thereupon. The flange 33 of the strip 32 is also arranged for being moved toward and from the extension members 17 of the bar, and on the free end of the strip 32 is a clip 34 adapted to releasably lock the strip 32 to the bar 10. The clip 34 is preferably provided by bending 75 the free end of this strip in the formation of a hook so as to be guided over the shoulders 14 and 15 of the bar.
- The retaining element 25 is designed especially to permit the form of razor blade 80 22, Fig. 6, to be removably held in the holder for being sharpened, and to accomplish this the blade is positioned on the lug 16 as well as on top of the extension members 17 of the bar 10 so that the bead 23 of 85 the blade will abut against the extension members, as shown in Fig. 2. The retaining element 25 is then swung from its position in engagement with the shoulder 14 of the bar 10 over the blade and transversely over 90 the bar 10 so that the clip or hook 34 may be guided over the shoulder 15 of the bar. The clip 34 being provided accordingly on the strip 32 this strip will thereby be disposed on top of the blade so that its flange 33 will 95 abut against the edge of the bead 23 opposite to its edge which is in contact with the extension members 17, and the razor blade will in turn be releasably clamped in the holder to allow the blade to be sharpened 100 similarly to sharpening the razor blades 18 and 19.
- In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to 110 make such changes as fairly fall within the scope thereof.
- Having thus described my invention, I claim as new and desire to secure by Letters Patent:—
- 115 The combination, in a razor blade holder, with a flat body member with shoulders at its ends and having spaced upwardly protruding extension members for removably receiving a safety razor blade, of two strips 120 with one of their corresponding ends pivoted to the body member for being separately swung upon the blade, one strip having laterally projecting fingers and the other having a projecting flange to coat with the 125 130

extension members for clamping the blade on the body member, and a clip on the second end of each strip, each clip being detachably engageable with one of the shoulders of the body member for releasably locking the body member and the strips together.

This specification signed and witnessed this 31st day of October, A. D. 1917.
